SLICING MACHINE

Charles T. Walter, Chicago, Ill., assignor to Swift and Company, Chicago, Ill., a corporation of Illinois

Application November 27, 1931, Serial No. 577,443

9 Claims. (Cl. 146—95)

The invention relates to a bacon slicing machine.

The object of the present invention is to improve the construction of bacon slicing machines, more especially the means for feeding a slab of bacon to the cutting element, and to provide a simple, practical and efficient bacon slicing machine equipped with conveyor rolls having worm threads for feeding the bacon and arranged to neutralize and eliminate side thrust so that a slab of bacon will be fed in a straight line to the cutting element without any material play or movement induced by the spiral conveyor rollers.

A further object of the invention is to provide a bacon slicing machine of this character in which the usual gap which commonly occurs between the end of the conveyor and the cutting element will be eliminated and the conveyor enabled to form a support for the bacon closely adjacent to the knife blade of the cutting element.

Another object of the invention is to eliminate the bearings of the conveyor rollers at the ends adjacent the cutting element and to provide a supporting means for the conveyor rollers which will afford the rollers a continuous support throughout their length and maintain the rollers in proper position by gravity.

With these and other objects in view, the invention consists in the construction and novel combination and arrangement of parts hereinafter fully described, illustrated in the accompanying drawings, and set forth in the claims hereto appended, it being understood that various changes in the form proportion and minor details of construction, within the scope of the claims, may be resorted to without departing from the spirit of the invention or sacrificing any of the advantages thereof.

In the drawings:

Figure 1 is a side elevation of a bacon slicing machine constructed in accordance with this invention.

Fig. 2 is a longitudinal sectional view taken substantially on the line 2—2 of Fig. 3.

Fig. 3 is a transverse sectional view taken substantially on the line 3—3 of Fig. 2.

Fig. 4 is a horizontal sectional view taken substantially on the line 4—4 of Fig. 2.

In the accompanying drawings, in which is illustrated the preferred embodiment of the invention, the slabs 1 of bacon are fed to a conventional rotary slicing knife 2 by worm threaded conveyor or feed rollers which are preferably four in number and extend longitudinally of the bacon slicing machine. The rollers are arranged in

pairs and the worm threads 4 of the adjacent rollers spiral in opposite directions to neutralize side thrust and to enable the slabs of bacon to be fed forwardly to the rotary slicing knife in a straight direction without any lateral movement induced by the worm threaded conveyor rollers. These conveyor rollers are positioned so that the upper surfaces of the several rollers extend along and are tangent to a horizontal plane common to all of the rollers, whereby a flat strip of bacon is maintained substantially flat while being conveyed in a forward longitudinal direction by the rollers to the rotary slicing knife. While two pairs of reversely threaded worm conveyors are illustrated in the accompanying drawings, it will be clear that the number of pairs of conveyor rollers may be varied. These feed rollers collectively provide what may be termed a feeding or feed table upon and by which flat slabs of bacon can be fed in a longitudinal forward direction to the rotary slicing knife 2.

The bacon slicing machine is provided with a suitable framework, and the spiral or worm threaded conveyor rollers at their front or outer ends terminate closely adjacent the rotary slicing knife to eliminate the gap which commonly occurs between the rotary slicing element and the adjacent end of the conveyor. These conveyor rollers are mounted in a cradle bearing 5 arranged in a horizontal position beneath the conveyor rollers and extending across the frame of the machine and rigidly secured to the same at opposite sides thereof by screws or bolts 6 or other suitable fastening means. The cradle bearing, which may be of any suitable material, compensates for lack or axial support for the conveyor rollers and consists of a rectangular body provided in its upper face with roller receiving grooves 7 and having journal bearings 8 at the inner or rear ends of the grooves, which are segmental in cross section to conform to the configuration of the conveyor rollers. The conveyor rollers rest upon the curved walls of the bottoms of the grooves 7 and are supported throughout their entire length and are maintained in proper position by gravity. The bearing grooves 7, which extend longitudinally of the bacon slicing machine, relieve the journal bearings of strain, and the said conveyor rollers are provided at their inner or rear ends with suitable shaft extensions or journals 9 which project beyond the inner or rear end of the cradle bearing and have mounted on them spur gear wheels 10 forming a train of gears which connect the conveyor rollers and cause the adjacent rollers to rotate in opposite directions to effect a forward

feeding of the slabs of bacon by the spiral webs or flanges 4. The journal bearings are omitted at the front or outer ends of the conveyor rollers, which present flat surfaces at their front ends 5 adjacent the inner face of the rotary knife 2. The roller gears mesh with one another, and one of the said gears meshes with a spur gear wheel 11 of a short longitudinal shaft 12 journaled in a suitable bearing 13 of the framework 10 of the machine and provided at one end with the said spur gear wheel 11 and at the other end with a bevel gear wheel 14 which meshes with a bevel gear wheel 15 of a lower transverse shaft 16. The lower transverse shaft 16, which is journaled in a suitable bearing 17 at one side of the frame of the machine, projects beyond the said side of the machine and is provided at its outer end with a pulley 18 which is connected by a belt 19 with a pulley 20 of an upper transverse 15 shaft 21. The upper transverse shaft 21, which is journaled in a suitable bearing 22 of the frame of the machine, projects beyond the same and is provided at its outer end with the said pulley 20. The inner end of the transverse shaft 21 is provided with a bevel gear 23 which meshes with a bevel gear 24 mounted on a longitudinal power driven shaft 25 which carries the rotary cutting element 2. The shaft 25, which is located at the top of the frame of the machine, is journaled 20 in suitable bearings 26 and 27 thereof and the rotary cutting element is secured to the outer or front end of the said shaft 25, which is provided at its inner or rear end with a pulley 28 which is connected by a belt 29 with a pulley 30 of the shaft 31 of an electric motor 43, but any other suitable form of motor may, of course, be employed, and any other suitable means may be provided for connecting the motor with the knife carrying shaft 25 of the slicing machine. 25

When the motor is in operation the shaft 25 is rotated and motion is communicated from the shaft 25 through the upper and lower bevel gears and the belt 19 to the conveyor rollers for feeding slabs of bacon to the rotary cutting element. 30

The slabs of bacon which are flat are maintained in contact with the conveyor or feed rollers by means of a plurality of superimposed pressure or presser rollers 32 located above and resting upon the slabs of bacon in the machine and urged downwardly by coiled springs 33. The pressure rollers, which extend transversely of the machine, are preferably cylindrical and are provided at their ends with journals 34 which are mounted in vertically movable bearing blocks 35 arranged contiguous to one another and located at both ends of the pressure rollers and provided with vertical rods 36 which are slidable in guide openings 37 of longitudinal guide bars 38 adjustably secured to the frame of the machine at 35 opposite sides thereof by slot and bolt connections 39 and 40 for varying the tension of the springs and the pressure of the upper rollers 32 upon the slabs of bacon. The guide bars 38 consist of angle bars having vertical and horizontal flanges, the vertical flanges being fitted against the sides of the frame of the machine, as clearly illustrated in Fig. 3 of the drawings, and the horizontal flanges projecting inwardly from the sides of the frame and provided with the guide openings 37. The bearing blocks 35 are slidably vertically independently of one another to permit the pressure rollers to adjust themselves to inequalities in the upper surface of the slabs of bacon. The presser rollers 32 being cylindrical and the conveyor rollers being arranged so that a rela-

tively flat general feeding surface is provided thereby, it will be appreciated that the cylindrical pressing rollers can properly press the strip of bacon being fed towards and in proper engagement with each of the four conveying rollers or feed screws. 5

The vertical rods 36 of the bearing blocks may be of any cross sectional formation, and they are provided at their upper ends with pins or keys 41 located at the upper faces of the horizontal flanges of the bars 38 and adapted to limit the downward movement of the pressure rollers, but any other suitable form of stop may, of course, be provided. The bars 38 are adapted to be raised or lowered by means of the slot and bolt 15 connections 39 and 40 to vary the spring pressure of the rollers 32 upon the slabs of bacon. 10

The frame of the machine is provided at the inner or rear end with a suitable table or platform 42 to receive the slabs of bacon, which are 20 moved forwardly by hand to engage the front end of the bacon between the superimposed pressure rollers and the lower conveyor rollers, and when a slab of bacon is properly engaged between the upper pressure rollers and the lower conveyor rollers, it will be positively fed forward in a straight line by the worm threaded conveyor rollers or shafts without any lateral movement, and the said roller conveyors, which terminate in a plane adjacent to the inner face of the rotary knife 2, support the end of the slab of bacon while the same is being cut. By eliminating the journal bearings at the front or outer ends of the conveyor rollers, the gap or space which is commonly left between the ends of the 25 conveyor and the cutting element is closed, thereby providing both a feed and a support for the front or outer end of the bacon to practically the plane of the inner face of the knife 2. 30

What is claimed is:

1. A bacon slab slicing machine comprising a cutting element, means for feeding the material to the cutting element including horizontally and longitudinally disposed conveyor rollers journaled only at their inner or rear ends and having their front ends arranged contiguous to the cutting element, thereby eliminating any gap between the end of the feeding means and the cutting element, which said conveying rollers are disposed so that the upper feeding surfaces thereof all lie in a common horizontally extending plane, transversely and horizontally disposed longitudinally-spaced cylindrical presser rollers arranged above the conveyor rollers, and spring means for yieldably pressing the presser rollers downwardly toward the conveyor rollers for continuously pressing and maintaining material being sliced into feeding contact with the several conveyor rollers. 45

2. A slicing machine including a cutting element, means for feeding material to the cutting element including longitudinally disposed conveyor rollers arranged in pairs and mounted against vertical movement in horizontal alignment and all of substantially the same diameter throughout their lengths, the adjacent rollers having worm threads throughout their lengths spiralling in opposite directions, gears connecting the rollers for rotating adjacent rollers in opposite directions, and presser rollers arranged transversely above the conveyor rollers for engagement with the material fed by the conveyor rollers to maintain the material in feeding contact with the latter. 55

3. A slicing machine comprising a cutting element, means for feeding the material to the cutting element including longitudinally disposed conveyor rollers disposed in horizontal alignment and journaled only at their inner ends and having their front ends arranged contiguous to the cutting element and eliminating undue gap between the outer ends of the conveyor rollers and the cutting element, and means to support the conveyor rollers between the ends thereof, said conveyor rollers being of substantially the same diameter throughout their lengths, and presser rollers yieldably disposed above the conveyor rollers at an angle thereto and in close side by side relation to press upon the material to maintain the material in intermediate engagement with the conveyor rollers.

4. A slicing machine comprising a cutting element, means for feeding the material to the cutting element including longitudinally disposed conveyor rollers disposed in horizontal alignment and journaled only at their inner ends and having their front ends arranged contiguous to the cutting element and eliminating undue gap between the outer ends of the conveyor rollers and the cutting element, means to support the conveyor rollers between the ends thereof, and means including transversely disposed vertically yieldable presser rollers for continuously pressing material downwardly against the conveyor rollers to insure the forward longitudinal feeding of the material by said conveyor rollers.

5. A slicing machine comprising a frame, a cutting element, means for feeding material to the cutting element including longitudinally disposed conveyor rollers mounted in horizontal alignment and all of substantially the same diameter throughout their lengths and each having its outer end contiguous to the cutting element to reduce to substantially a minimum the gap between the cutting element and the feeding means, the adjacent rollers having spiral flanges extending throughout the lengths thereof and projecting outwardly at a right angle to the plane of the rollers, the convolutions of the flanges being spaced apart and the peripheral edges thereof supporting the meat above the bodies of the rollers across the spiral channels formed by the convolutions of said spiral flanges, and gears connecting the rollers for rotating adjacent rollers in opposite directions.

6. A slicing machine comprising a frame, a cutting element, means for feeding material to the cutting element including longitudinally disposed conveyor rollers of substantially the same diameter throughout their lengths and arranged in pairs relatively close together in horizontal alignment, the adjacent rollers having spiral flanges extending therefrom in opposite directions, to neutralize side thrust and prevent tendency toward cross feeding of the material, the peripheral edges of said spiral flanges supporting the material above the bodies of the rollers, gearing connecting the rollers for rotating adjacent rollers in opposite directions, and presser rollers arranged transversely above the conveyor rollers

for engagement with the material fed by the conveyor rollers to maintain the material in feeding contact with the peripheral edges of said spiral flanges.

7. A slicing machine comprising a frame, a cutting element, means for feeding material to the cutting element including longitudinally disposed conveyor rollers having their outer ends disposed close to the cutting element to practically eliminate gap between the cutting element and the outer ends of the rollers, the rollers having reversely arranged spiral flanges projecting outwardly from the rollers and extending in opposite directions to neutralize side thrust and prevent tendency of cross feeding of the material, said conveyor rollers being arranged in horizontal alignment and each being of the same cross sectional diameter throughout its length and the spiral flanges being of the same width throughout their length and supporting the material out of contact with the bodies of the rollers across the spiral space between the convolutions of the spirals, operative connections between the conveyor rollers, and means above the conveyor rollers to yieldably press downwardly upon the material to maintain the same in feeding contact with the peripheral edges of the spiral flanges of the conveyor rollers.

8. A bacon slab slicing machine comprising a cutting element, means for feeding the slab to the cutting element including longitudinally disposed conveyor rollers journaled only at their inner ends and having their front ends contiguous to the cutting element so as to eliminate undue gap between the outer end of the feeding means and the cutting element, said conveyor rollers all lying relatively close together in the same horizontal plane, and spring actuated presser rollers arranged transversely above the conveyor rollers for continuously yieldably pressing upon and maintaining the slab in feeding engagement with the conveyor rollers.

9. A bacon slab slicing machine comprising a cutting element, means for feeding the slab to the cutting element including longitudinally disposed conveyor rollers of substantially the same diameter throughout their lengths and arranged close together in the same horizontal plane and having their front ends contiguous to the cutting element so as to eliminate undue gap between the outer end of the feeding means and the cutting element, the adjacent rollers having spiral flanges extending therefrom in opposite directions to neutralize side thrust and prevent tendency toward cross feeding of the material, the peripheral edges of the spiral flanges supporting the material above the bodies of the rollers, means connecting the rollers for rotating adjacent rollers in opposite directions, and presser rollers arranged transversely above the conveyor rollers for engagement with the material fed by the conveyor rollers to maintain the material in feeding contact with the peripheral edges of said spiral flanges.

CHARLES T. WALTER. 65
